UNITED STATES PATENT OFFICE

HARRY GEORGE SUTTON, OF SYRACUSE, NEW YORK, ASSIGNOR, BY MESNE ASSIGNMENTS, TO UNITED STATES HOFFMAN MACHINERY CORPORATION, OF NEW YORK, N. Y., A CORPORATION OF DELAWARE

PRESS

Application filed September 23, 1926. Serial No. 137,291.

This invention pertains to presses designed to be utilized primarily for the pressing of garments.

The main object of the invention is to provide a relatively simple structure wherein the head, when the press is open, stands a considerable distance to the rear of the buck or fixed pressing element and moves forwardly over the buck in direct alignment therewith and then moves downwardly to pressing position in a substantially right line whereby any dragging of the head across the goods is precluded. By this arrangement the operator may secure a proper lay of the goods upon the buck or fixed pressing element and hold it in such position as the head is swung forwardly and over the buck prior to the downward movement of the head into pressing relation with the buck. The clearance between the head and the buck, after the head has been moved forwardly in alignment with the buck, is such that the operator may retain his hold upon the garment and shift the garment, if need be, prior to, or during the lowering of the head. In the reverse movement of the press, the head first moves upwardly in a right line and then swings rearwardly to full open position.

A further object of the invention is to provide a base or standard which carries guideways or cam slots, which elements cooperating with rollers secured to the head supporting frame give or impart to the head and its supporting frame the movements above specified.

A still further object of the invention is to provide a simple means whereby the head supporting frame may be moved downwardly so as to effect the forward motion and the ultimate downward motion to produce the pressing operation. Means is provided tending at all times to raise the head supporting frame to its highest position in which position the head is fully elevated and carried to the rear and clear of the buck.

A still further object of the invention is to provide a frame of sheet metal which is light in construction and yet quite rigid, the head supporting member being likewise formed in a like manner.

With these and other objects in view, reference is had to the annexed drawings wherein,

Figure 1 is a vertical longitudinal section of the press, the head being shown in its fully opened and rearward position in full lines and in its intermediate position in dotted lines, that is to say, prior to its final downward movement to effect the pressing operation;

Figure 2 a vertical sectional elevation showing the head fully lowered into pressing relation and the treadle lever locked;

Figure 3 a vertical sectional elevation taken on the line III—III of Figure 1 looking toward the rear of the press; and

Figure 4 a transverse horizontal sectional view taken on the line IV—IV of Figure 1.

The base or frame of the machine may be said to comprise a base plate or casting 1, a top plate or casting 2, both being preferably flanged to provide strength, and an intermediate body element formed from two similar members 3 and 3^a of sheet steel pressed to form. These parts are secured together in any approved manner as by electric welding, riveting or otherwise. The members 3 and 3^a are substantially L-shape in cross section, as will be best seen upon reference to Figure 4, and their lower portions preferably extend into the member 1 to which they are secured in order to impart rigidity to the frame. The edges of the members at their forward portion are separated, forming a vertical opening or slot 4 which extends the height of the frame.

Rising from the top plate 2 is a buck support 5 upon which in turn is secured the buck 6, the face of which may have any desired contour.

The head is denoted by 7 and is so shaped as to cooperate with the face of the buck. These members may be provided with suitable padding, not shown, and will likewise be provided with outlets, not shown, for the connection of pipes through which steam may enter for the purpose of heating the same and ejecting steam upon the garment. Suitable vacuum or suction pipes will be employed but none of these pipes are shown as

they form no part of the present invention. The head 7 is secured to the forwardly extending arm or member 8 of a supporting frame. The lower portion or arm 9 of said frame is inclined forwardly to a slight extent from a right angle with reference to the upper member to which the head is attached. In other words, the supporting frame takes the general outline of an inverted L. Preferably this supporting frame or element is formed from sheet steel bent to form and may be said to comprise a relatively wide body portion provided with rearwardly extending side flanges 10 and 10^a. A handle 11 is provided at the forward end of the arm 8 so that the frame and the head may, if desired, be drawn forwardly by hand.

Each of the side members 3 and 3^a is provided with two slots or openings and secured to said plates adjacent said openings are bearing elements adapted to receive guiding rollers secured to the head supporting frame. Inasmuch as the corresponding slots and tracks in each of the members 3 and 3^a are alike in form and function, one set only will be described and the exponent ^a will be applied to the reference numerals upon the second set.

Adjacent the lower forward portion of the member 3 there is formed a slot 12, see Figure 1, the lower portion of which is vertical, or substantially so, while the upper portion is inclined rearwardly to a slight extent. Secured to the plate is a member or casting 13, Figure 4, having an opening therein of the same contour as the slot 12. A second slot is formed in the upper portion of the plate adjacent its rear, said slot being denoted by 14. The lower portion of this slot stands in parallelism with the lower portion of slot 12 while the rear portion thereof is inclined only to a slight extent above the horizontal.

Secured to the outer face of the plate 3 adjacent the slot or opening 14 and having an opening therein of the same contour as the slot, is a track or guideway 15, see Figure 3.

Attached to the lower end of the head supporting member is a bracket 16, see Figure 4, and mounted in said bracket is a stud axle or bolt 17 which forms the support for a roller 18 having a flange 19 at its inner end which bears against the inner face of the plate 3. The bracket may be provided with a socket adapted to receive an upwardly extending bumper 20 of rubber or the like, which bumper is adapted to coact with a pad 21, see Figure 3, carried by the under face of a bracket 22 secured to the side wall of the member 3. This bracket and the associated parts, along with the bumper 20 form stops to prevent the head from swinging too far back and from placing strain upon the rollers, heretofore described, and their associated elements and likewise upon the upper rollers. The

upper roller 23 having a flange 24 is carried by a stud axle 25 mounted in a bracket 26 secured to the head supporting element or frame.

All of the rollers are preferably adjustably mounted so as to insure fair bearing between them and the fixed frame to prevent any side movement of the head supporting frame.

To prevent the frame, and the head supported thereby, from being thrown back violently and placing undue strain upon the parts, there is preferably employed a snubber of any known form, the snubber casing being denoted by 27, the strap 28 of which extends rearwardly and is secured to the head frame in any suitable manner as by an eye bolt 29. The snubber frame 27 is secured to one side of a heavy bracket or inverted column 30 rigidly affixed to the under face of the head-piece 2 of the frame.

The lower end of the member 30 is bifurcated, see Figure 3, and pivotally mounted upon a shaft 31 in the lower end of the bracket is a lever of bell-crank form. The lower arm 32 of said lever is bifurcated and in the outer extremity thereof there is pivotally mounted a cross pin 33 forming the support for a block 34 which is embraced between the bifurcated portions of the arm. The block and pin, see Figure 1, have aligning openings extending therethrough through which extends the reduced upper end of a link 35. Pinned to the upper end of said member 35, above the block, is a hand piece 36 by which the link may be rotated to turn its lower threaded end into or out of a block 37 which latter in turn is pivotally mounted at its lower end upon a cross shaft 38 carried by arms of a bracket 39 secured to the lower end of the head supporting frame. The members 35 and 37, in effect, form one link or element of a toggle the other element of which is the arm 32. The upper arm 40 of the elbow lever is bifurcated, see more particularly Figure 3, and a cross pin or shaft 41 is secured therein. Said shaft forms the support for the upper ends of a pair of draw links 42 and 42^a the lower ends of which are secured to a cross pin 43 mounted in the arms 44 and 44^a which extend inwardly from a treadle 45, see Figure 4. Said arms are rigidly secured to the forward end of a pair of bars 46 and 46^a which extend rearwardly of the press and are fulcrumed upon a cross bar or shaft 47, which latter finds its support in the upwardly extending lugs 48 and 48^a shown as formed as an integral portion of the base member 1.

The bars 46 and 46^a, together with the arms 44 and 44^a and the treadle 45, form a treadle lever which, when depressed by the operator draws the links downwardly and rocks the bell-crank lever about its fulcrum 31 and tends to bring to straightened position the toggle composed of the member 31 and the members 35 and 37.

A pivoted latch 49 is carried by the treadle lever and when said lever is depressed to its full position the hooked portion thereof engages a fixed portion of the base element 1.

5 A bumper 50 carried by a bracket 51 fixed to the base member 1 stands in line with the cross piece 52 formed as an integral part of the treadle and serves to relieve the operator from jar or shock when the treadle is carried 10 down to its full extent.

In order to effect an upward movement of the head carrying frame and to cause the rollers to move upwardly in the slots, there is provided spring means secured between a 15 fixed portion of the bed of the machine and the lower portion of the swinging and tilting head carrying frame. In the instant case, two springs are shown designated respectively by 53 and 53^a. The springs may be attached to the fixed frame of the machine and to the head frame in any suitable manner and in the present instance there is shown a hook or eye 54 rigidly secured to the frame member 2 with which there engages a similar 20 member 55, the lower end of which is threaded into a block 56 screwed into the upper end of the spring. The lower end of the spring carries a similar block into which is threaded a stem 57 projecting upwardly from a bifurcated yoke or block 58 which is pivotally connected to a bracket 59 secured to the lower end of the head carrying frame 8.

A work table 60 is shown secured to the upper frame member 2.

35 The operation of the machine may be briefly stated as follows: Assuming that the parts are in the position shown in full lines in Figure 1, the operator may draw the head frame and the head forwardly by taking hold of the handle 11 and bringing it to the position shown in dotted lines in Figure 1; or such action may be effected by depression of the treadle lever. When the head is in the position shown 40 in the dotted lines, the rollers 18 and 23 and 18^a and 23^a will occupy the position shown in the dotted lines in Figure 1. In other words, they will have passed out of the rearwardly inclined portions of the slots or ways 45 and will be in line with the vertically disposed portions of said slots. Further downward movement of the treadle lever will then bring the arm 32 of the bell-crank and the link 35 to the position shown in Figure 2, the 50 links 42 and 42^a drawing down upon the upper arm of the bell-crank and forcing the link 35 downwardly and thereby drawing the head frame downwardly and moving the head in a right line toward the buck or fixed 55 pressing element 6 of the machine.

60 The latch 49, when the treadle is fully depressed, will engage the fixed member on the frame element 1 and the press will thus be held locked in its closed position. It may be readily opened by merely depressing the

forward end of the latch and the springs will then tend to raise the head frame and the head and, as the rollers move upwardly in the slots or cam-ways, the frame first moves upwardly to the position shown in dotted lines, Figure 1, and then rearwardly to the full line position shown in said figure.

70 The snubber 27 will prevent the head from swinging back too rapidly and thus placing strain upon the parts. Furthermore, the spring action of the snubber will, to a degree, assist in drawing the head supporting frame forwardly.

75 It will be noted that when the head is in its rear position the springs are not under tension, hence but little effort is needed to move the head forwardly to the dotted line position. The linkage, moreover, is such that an extremely heavy pressure may be applied to the head through the frame and the press is thus effective for both light and heavy work. The degree of pressure may, of course, be varied by changing the effective length of the link 35.

80 By having the frame-work of the machine constructed of sheet steel it is at once light and rigid. So too by making the head carrying frame 8 of the same material the frame is light and yet will effect all the pressure that is needed to make the press highly efficient.

85 The head carrying frame will allow the head to tilt where, for instance, a heavy piece of goods is under one end and a light piece under the other and yet said head will always come back to its true alignment when the pressure is removed. In other words, the sheet steel of which the head frame is formed may be thrown out of true position up to the elastic limit of the metal and always come back to position.

90 It is, furthermore, to be noted that the rollers on the opposite sides of the head frame are spaced a considerable distance apart and there is little or no tendency for the frame to weave or twist. Again there is no localized bearing between the main frame and the head frame, a feature of manifest advantage particularly over those constructions which employ an arm or lever pivotally supported on or by a shaft.

95 What is claimed is:

1. In a garment press the combination of a fixed pressing element; a movable pressing element adapted to cooperate therewith; a frame for supporting said fixed element; a supporting element for the movable pressing element mounted for movement with reference to the frame; positive guiding means independent of any press actuating means, interposed between said frame and the supporting element acting to constrain motion of the supporting element to a substantially right line separation of said movable pressing element from the fixed element and then a lateral swinging movement; spring means

acting at all times to elevate said frame and to normally hold it in such position; and operator operated means for drawing said frame downwardly in opposition to said spring means.

2. In a garment press the combination of a fixed frame; a pressing element mounted thereon; a movable pressing element; a supporting frame having an upper overhanging portion to which latter the movable pressing element is attached, said frame being movable with reference to the fixed frame; cooperating confining guideways and rollers carried by said respective frames and forming the sole means for directing the movement of the supporting frame; spring means normally acting to move the supporting frame upwardly and to maintain it in such position; and means under the control of the operator for drawing the head supporting frame downwardly in opposition to said spring means.

3. In a garment press the combination of a fixed frame; a pressing element mounted thereon; a movable pressing element; a supporting frame having an upper overhanging portion to which latter the movable pressing element is attached, said frame being movable with reference to the fixed frame; cooperating guide ways and members carried by said respective frames for positively directing the movement of the supporting frame; spring means normally acting to move the supporting frame upwardly and to maintain it in such position; and means under the control of the operator for drawing the head supporting frame downwardly.

4. In a garment press the combination of a fixed frame; a pressing element mounted thereon; a movable pressing element; a supporting frame having an upper overhanging portion to which latter the movable pressing element is attached; a pair of confining guide ways formed upon each side of the fixed frame, the ways of each pair being provided with a substantially vertically disposed lower portion with the upper portions inclining rearwardly; rollers carried by the supporting frame and extending into said ways; spring means acting upon the supporting frame to move the same upwardly; and means acting in opposition thereto to move the supporting frame downwardly.

5. In a garment press the combination of a fixed frame; a pressing element mounted thereon; a movable pressing element; a supporting frame for the latter; a pair of confining guide ways formed upon each side of the fixed frame, the ways of each pair being provided with a substantially vertically disposed lower portion with the upper portions inclining rearwardly; rollers carried by the supporting frame and extending into said ways; means acting upon the supporting frame to move the same upwardly; and a

toggle mechanism interposed between the lower end of the supporting frame and the fixed frame to move the supporting frame downwardly.

6. In a garment press the combination of a fixed frame the side walls whereof are spaced apart and the frame being open to the rear; cooperative pressing elements one whereof is movable with reference to the other; a supporting frame for said movable pressing element, said frame having the form, substantially, of an inverted L with the lower end extending inwardly of the sides of the fixed frame; vertically spaced rollers extending from the lower portion of each of the sides of the supporting frame, each roller extending into a confining cooperating guideway, one for each roller, formed in the sides of the fixed frame, said rollers and guideways forming the sole means for guiding the head supporting frame; means for lowering said supporting frame; and spring means connected to the lower portion of the supporting frame and a fixed portion of the press acting at all times to elevate said frame.

7. In a garment press the combination of a fixed frame; a pressing element mounted thereon; a movable pressing element; a support therefor, said support extending rearwardly of and downwardly therefrom; guide members secured to said support; cam tracks for said guide members, said tracks being arranged in vertically disposed pairs, the slots of each pair having parallel portions which constrain the support to right line motion when the pressing elements are near each other and non-parallel portions which impart a compound movement to the support when the press elements are more remote from each other; means connected to the support for drawing its lower end downwardly; and means directly connected to said support acting to elevate the same.

8. In a garment press, a buck; a head; a movable frame supporting said head; rollers supporting said frame; and guides for the rollers arranged in vertically disposed pairs having parallel portions and divergent portions arranged to cause the head to move in a right line upwardly from pressing position and then rearwardly with compound motion clear of the buck.

9. In a garment press the combination of a main frame; a buck mounted on said frame; a head; a movable frame to which the head is attached; a plurality of laterally extending and vertically spaced rollers carried by each side of the lower portion of the movable frame, each of said rollers extending into a guiding slot formed in the main frame, said slots being vertically spaced and so contoured as to impart a right line movement to the movable frame as the same is moved to final pressing position,

said rollers forming in conjunction with said slots the sole guiding means for said movable frame; and means for shifting the frame.

5 10. In a garment press the combination of a fixed main frame; a buck thereon; a pressing head; a supporting frame for the head, said frame having a rear downwardly extending portion; cooperating guides and rollers carried by the frames for supporting said supporting frame and controlling its direction of movement; a treadle lever fulcrumed at the rear of the main frame; a bell-crank lever fulcrumed upon a fixed portion of the press; a link connected with the lower arm of said bell-crank lever and likewise connected to the lower end of the downwardly extending portion of the head supporting frame; and at least one draw link 15 connecting the treadle lever with the upper arm of the bell-crank lever.

11. A garment press as set forth in claim 10 provided with spring means acting upon the lower end of the head supporting frame 20 to urge the same upwardly.

12. In a garment press the combination of a fixed frame comprising two vertically disposed side members standing in spaced relation; a buck supported thereby; a head 25 adapted to cooperate with the buck; a head carrying frame having a downwardly extending portion and a forwardly extend portion to which latter the head is secured; a pair of cam follower elements extending outward from each side of said downwardly extending portion; a pair of vertically spaced cams in each of said side members arranged to confine said rollers to definite paths of motion the two cams in each side 30 member having parallel portions and divergent portions whereby the head is constrained to right line motion when adjacent the buck and to compound swinging motion toward and from a position over the buck; 35 and means for actuating said head carrying frame comprising a toggle directly connected to the head carrying frame and to a fixed portion of the press to move said head carrying frame and to develop a rapidly increasing leverage by movement of the toggle 40 toward straightened position as the head approaches pressing relation with the buck.

45 In testimony whereof I have signed my name to this specification.

50 55 HARRY GEORGE SUTTON.

CERTIFICATE OF CORRECTION.

Patent No. 1,881,000.

October 4, 1932.

HARRY GEORGE SUTTON.

It is hereby certified that error appears in the printed specification of the above numbered patent requiring correction as follows: Page 4, lines 99 and 113, claims 7 and 8, respectively, for "disposed" read displaced; page 5, line 40, claim 12, after "parallel" insert the words right line; and that the said Letters Patent should be read with these corrections therein that the same may conform to the record of the case in the Patent Office.

Signed and sealed this 29th day of November, A. D. 1932.
